UNITED STATES PATENT OFFICE

HENRY SPONGBERG, OF LOOMIS, NEBRASKA

VARIABLE TUNING CONDENSER

Application filed September 21, 1927. Serial No. 221,058.

This invention relates to improvements in variable tuning condensers for radio receiving apparatus and has as its general object to provide a condenser which will substantially eliminate interference of broadcast programs with one another, the invention 5 contemplating the provision of a condenser which may be so adjusted as to permit the tuning in of a broadcast station to the exclusion of other stations broadcasting on approximately the same wave length.

Another object of the invention is to provide a variable condenser so constructed that it may be adjusted as to render the receiving 15 apparatus, of which it constitutes a part, more sharply tuned than is possible by the use of condensers of the ordinary construction.

Another object of the invention is to provide 20 a variable condenser embodying two condenser units the combined capacity of which is equal to the proper capacity for the particular radio frequency transformer with which the condenser is associated, in combination with means whereby the units may be independently accurately adjusted to provide for a finer degree of adjustment than is possible with the use of the ordinary types of variable condensers.

Another object of the invention is to provide, 25 in a variable condenser embodying two condenser units and vernier means for adjusting the units independently of each other, novel means whereby the units may be simultaneously adjusted, where a quick adjustment of the units throughout a relatively wide range, is desirable, as for example when shifting from one to another of two broadcast stations of relatively widely different 30 wave lengths.

While the accompanying drawings and the description which is to follow, constitute a disclosure of the preferred embodiment of the invention, it will be understood that 35 various changes may be made within the scope of what is claimed.

In the accompanying drawings:—

Figure 1 is a front elevation of the condenser embodying the invention mounted 40 upon the panel of a receiving set,

Figure 2 is a vertical transverse sectional view taken substantially on the line 2—2 of Figure 3 looking in the direction indicated by the arrows and illustrating, in elevation, the forward head of the condenser and the manner of mounting the frame upon the panel, 55

Figure 3 is a vertical front to rear sectional view taken axially through the condenser mounted upon the panel, 60

Figure 4 is a vertical transverse sectional view through the condenser taken substantially on the line 4—4 of Figure 3 looking in the direction indicated by the arrows, 65

Figure 5 is a top plan view of the condenser mounted upon the panel, 70

Figure 6 is a vertical transverse sectional view taken substantially on the line 6—6 of Figure 3 looking in the direction indicated by the arrows, 75

Figure 7 is a sectional view illustrating one of the vernier shafts and the means for mounting the same.

The variable condenser embodying the invention is, of course, to be employed in connection with any of the well-known types of radio frequency transformers and inasmuch as it is adapted for universal use in connection with such transformers and is wired thereto in the usual manner, the drawings have been restricted to the condenser alone, the panel upon which the condenser is mounted, and which panel is indicated by the numeral 1, being however illustrated in the drawings in order to better exemplify the construction and operation of the condenser, 80

The body structure of the condenser includes a front head 2, a rear head 3, and an intermediate head 4, these heads being suitably spaced and of any suitable insulating material such for example as bakelite, the heads being maintained in proper spaced relation through the medium of rods 5 which are fitted through openings formed at suitable intervals in the peripheral portions of the heads 2, 3 and 4, the rods being provided each at one end with a head 6 to bind against the rear face of the head 3 and at its other end being threaded as at 7 and fitted into a respective one 100

of a plurality of threaded openings formed in the peripheral portion of the head 2, the intermediate portion of each rod 5 extending through a respective one of a plurality of openings 8 formed in the peripheral portion of the intermediate head 4. These rods 5 extend likewise through the usual openings 9 formed in the peripheral portions of the fixed plates of the condenser and through 10 spacing collars or washers 10 which are interposed between the fixed plates and which serve to properly space the same with respect to one another. As before stated the condenser, embodying the invention, embodies 15 two condenser units and one of these units is indicated in general in the drawings by the reference letter A and the other unit in general by the reference letter B, each unit including a group of the fixed condenser plates, 20 and the said fixed plates of the unit A being indicated by the numeral 11 and those of the unit B by the numeral 12. The movable plates of the two condenser units A and B are indicated respectively by the numerals 25 13 and 14, and at this point it may be stated that each condenser unit embodies an equal number of fixed and movable plates, and the plates are of the usual substantially semi-circular form and are of uniform dimensions, 30 so that each condenser unit is of the same capacity. As an example of the invention, and assuming that the radio frequency transformer requires a .0005 condenser, each condenser unit A and B will be of .00025 35 microfarad capacity.

The rotors of the two condenser units are mounted upon concentrically arranged shafts, and one of these shafts is indicated by the numeral 15 and is journaled at one end in a 40 suitable bearing 16 arranged within an opening in the head 3. A contact element 17 is secured through the rear side of the head 3 and contacts the rear end of the shaft 15, and to this contact element there may be connected one of the wires leading to the radio 45 frequency transformer. The numeral 18 indicates a sleeve which is exteriorly threaded at one end and fitted into an opening 19 formed in the intermediate head 4 near the 50 upper margin thereof, lock nuts 20 being preferably fitted onto this end of the sleeve and adjusted to bind against the opposite faces of the said head 4. The said sleeve 18 is fitted onto a reduced portion 21 of the shaft 15, and fitted rotatably on the sleeve 18 is a sleeve shaft 22 upon which are mounted the rotor plates 13 of the condenser unit A, these plates being suitably spaced by washers 23 like- 55 wise arranged on the sleeve shaft, and thus properly positioned between the stator plates 11 of the said unit. A fiber gear 24 is provided with an interiorly threaded hub 25 fitted onto a threaded portion of 60 the sleeve shaft 22, and a nut 26 is fitted onto the exteriorly threaded rear end portion of said shaft, the said rotor plates 13 being in this manner fixed upon the said sleeve shaft 22. In order that a vernier adjustment of the rotor plates 13 may be effected, a shaft 27 is journaled in a bushing 28 which is fitted into an opening 29 formed in the panel 1 and secured in place by a nut 30 which is threaded onto the inner end of the bushing and bears 75 against an ear 31 formed at the periphery of the head 2 and through which the inner end of the bushing extends. The bushing 28 is provided at its outer or forward end with an approximately circular head 32 which bears 80 against the outer face of a seating rim or flange 33 formed at the periphery of the cylindrical wall 34 of a housing 35 for the dials of the condenser, which dials will presently be more specifically described. A fiber pinion 36 is fixed upon the shaft 29 at the inner end of the bushing 28 and meshes 85 with the fiber gear 24. The inner end of the shaft 27 is journaled in an ear 37 which is provided at the lower edge of the intermediate head 4, and a collar 38 is fixed upon the shaft and engages against the forward side of said ear so as to prevent inward or rearward displacement of the shaft 27, the engagement of 90 the pinion 36 against the inner end of the bushing 28, preventing forward or outward displacement of said shaft. A knurled finger knob 39 is fixed upon the outer end of the shaft 27 and provides means whereby the shaft may be rotated so as to impart 95 rotary motion to the pinion 36 and to the gear 24 to effect rotary adjustment of the rotor plates 13 of the condenser unit A.

In order that the rotor of the condenser unit B may be adjusted, a fiber gear 40 is fixed upon the shaft 15 inwardly of the bearing 16 in the head 3, and a shaft 41 corresponding to the shaft 27 is rotatably journaled in a bushing 42 corresponding to the bushing 28 and mounted in the same manner as the said 105 bushing 28 and held in place upon the panel by a nut 43 threaded thereon. The said shaft 41 extends through an ear 44 likewise provided at the lower edge of the head 4, and is mounted at its inner or rear end in a suitable bearing 45 upon the head 3, a pinion 46 being 110 fixed upon the said shaft 41 and meshing with the gear 40, and a knurled finger knob 47 being fixed upon the forward end of the shaft 41 whereby rotary motion may be imparted 115 to the shaft to rotate the pinion 46 and impart rotary motion to the gear 40 and thus effect rotary adjustment of the rotor of the condenser unit B. The nut 43 which is fitted to the bushing 42, is tightened to bind against 120 an ear 48 likewise formed at the lower edge of the head 2 and at a point opposite the ear 31, it being understood that in this manner the lower portion of the said head 2 is secured 125 to the inner face of the panel. Bolts 49 are 130

fitted through the flange 33 of the housing 35 at the upper side of the housing and through the panel 1 and through ears 50 formed at the upper side of the head 2 at spaced points, nuts 51 being threaded onto the said bolts to bind against the said ears 50 and thus secure the upper portion of the head 2 to the inner face of the panel.

The sleeve shaft 22 is extended forwardly 10 through a bearing 52 arranged within an opening formed centrally in the head 2, and likewise through an opening 53 formed in the panel 1, and a dial 54 is provided upon this end of the shaft and is fixed with respect thereto. The said dial 54 is in the form of a circular disk which is provided upon its forward or outer face with a peripheral relatively wide flange 55 upon the face of which, throughout one-half the circumference of the 20 said flange, is provided a scale 56 comprising scale marks ranging from 100 to 200.

A flat circular dial 57 is fixed upon the reduced portion 21 of the shaft 15 in front of the dial 54 and is positioned within the bounds 25 of the flange 55 of the said dial 54, as clearly shown in Figures 1, 3 and 6 of the drawings, the dials being however sufficiently spaced to insure against mutual contact. The dial 57 is provided upon its face and at its periphery 30 with a scale 58 ranging from 0 to 100 and the said scale extends, as in the instance of the scale 56 for one-half the circumference of the periphery of the dial. The housing 35 for the dials 54 and 57 is formed in the upper 35 portion of its front wall with an arcuate sight opening 59 through which both of the scales 56 and 58 may be viewed, in the rotative adjustment of the dials, and an indicating element 60 such as a thin web of metal or a small wire, 40 may be positioned to span the sight opening 59 intermediate the ends thereof, and constitutes an indicator into registration with which the scale marks of the scales 56 and 58 may be brought.

45 At this point it will be understood that by manipulating the knurled finger knobs 39 and 47, the rotors of the condenser units A and B may be independently adjusted with great accuracy, and, due to the division of the 50 rotor and stator plates of the condenser into two groups and the provision of means for independently adjusting the rotors of the two units, the receiving set of which the condenser constitutes a part, may be very sharply and 55 accurately tuned. In other words, when the rotors of the two condenser units have been adjusted to a definite wave length to receive the broadcast waves from one station, and it is found that another station is interfering, 60 the rotor of the condenser unit B, for example, may be slightly adjusted so as to more accurately tune the set and eliminate the interfering stations.

Inasmuch as it will be desirable, at times, 65 to effect a more rapid adjustment of the rotors

of the condenser units, than can be effected by the adjustment of the vernier knobs 39 and 47, means is provided which will now be described. It will be observed by reference to Figure 3 of the drawings that the forward end of the shaft 21 is extended somewhat beyond the dial 57, and a sleeve 61 is fitted onto this extension of the shaft 21 and carries, at its inner end, which end abuts against the dial 57 at the center thereof, a collar 62 through which and the said end of the sleeve is threaded a screw 63 which bears against the reduced portion 21 of the shaft 15 and secures the sleeve upon the extension of this portion of the shaft. The front wall of the dial housing 35 is formed centrally with an opening 64, and a cylindrical hollow knob 65 is fitted through this opening and is provided at its inner end with an annular flange 66 which engages against the inner face of the said front of the dial housing 35. A collar 67 is fitted onto the sleeve 61 and is arranged within the finger knob 25 and held in place by a set screw 68, and a compression spring 69 is arranged within the knob and bears at one end against the said collar 67 and at its other end against the collar 62, the spring normally holding the knob shifted outwardly through the opening 64 and with its flange 66 bearing, as stated, against the inner side of the front wall of the housing 35. Four openings 70 are formed in the dial 54 and are equidistantly spaced with respect to each other and arranged in an annular series about the axis of the dial, and similar openings 71 are formed in the dial 57 and may be brought to position opposite the openings 70. A pair of studs 72 is provided upon the rear face of the flange 66 of the finger knob 65 and these studs are arranged to project through the openings 71, there being but two of said openings in the dial 57, and the ends of these studs terminate short of the plane of the front face of the said dial 54. Normally, therefore, 100 there is no connection between the dials 54 and 57 and, therefore, the dials may rotate independently of each other. However, when it is desired to rotate the dials in unison so as to quickly adjust the same without resorting to adjustment through the tedious and continuous rotation of the vernier knobs 39 and 47, for a considerable period of time, the finger knob 65 is grasped and pressed inwardly thus effecting engagement of the ends of the studs 72 in the openings 70 in the dial 54, the knob 65 being so rotated, at this time, as to rotate the dial 57 to a position where its openings 71, and consequently the ends of the studs 72, will be opposite a pair of the openings 70. In this manner, the two dials are connected for rotation in unison, and a further rotation of the knob 65 will effect such rotative movement of the said dials.

While the drawings illustrate two condenser units, it will be understood that three

or more units may be employed if desired. Having thus described my invention, what movement of the knob against the tension of said spring.

I claim as new is:—

1. A variable condenser comprising a plurality of units, each embodying a stator and a rotor, vernier means for independently adjusting the rotors of the units, the said rotors of the units embodying concentrically arranged shafts, dials upon the shafts, the said 10 dials being provided with openings adapted to be brought opposite to each other in the relative rotative adjustment of the dials, a rotatable knob having projections engaging through the openings in one of the dials the 15 said knob being shiftable to effect engagement of the said members in the openings in the other dial, and means yieldably holding the knob in inactive position.
2. A variable condenser comprising a plurality of units, each unit embodying a stator and a rotor, vernier means for independently adjusting the rotors of the units, the rotors of the units embodying concentrically arranged shafts, dials upon the shafts, and 25 means coacting with one of the dials and operable to rotate said dial independently of the other dial and independently of the vernier means and adjustable to coact with the said other dial to effect adjustment of the 30 dials in unison independently of said vernier means.
3. A variable condenser comprising a plurality of units, each embodying a stator and a rotor, vernier means for independently adjusting the rotors of the units, means operatively connected with the rotor of each unit for adjusting the respective rotor, and means associated with the adjusting means for the rotor of one unit and operable to adjust the 40 rotor independently of the vernier means and adjustable to coact with the adjusting means for the rotor of the other unit to actuate the same simultaneously with the first mentioned rotor adjusting means.
4. A variable condenser comprising a plurality of units each embodying a stator and a rotor, vernier means for independently adjusting the rotors of the units, the said rotors of the units embodying concentrically arranged shafts, dials upon the shafts, a casing 50 enclosing the dials and having a sight opening opposite the peripheral portions of the dials, a knob rotatably mounted in the front wall of the casing and having a head located within 55 the casing, a spring upon one of said shafts yieldably holding the knob in position with its head engaging against the said front of the casing, the said dials being provided with openings adapted to be brought opposite to 60 each other in the relative rotative adjustment of the dials, and studs upon the head of the knob projecting into the openings in one of the dials and adapted to be projected into the openings in the other dial to connect the two 65 dials for rotation in unison upon the inward

HENRY SPONGBERG.
